FIG. 2

Des. 220,749

FIG. 4

FIG. 1 is a perspective view of a combined packaging tray and cover showing my new design;

FIG. 2 is a top plan view thereof;

FIG. 3 is a sectional view taken on line 3—3 of FIG. 2 on an enlarged scale; and

FIG. 4 is a side elevation thereof on an enlarged scale. I claim:

The ornamental design for a combined packaging tray and cover, as shown.
